UNITED STATES PATENT OFFICE.

EDWARD H. SAXTON AND THOMAS C. QUAYLE, OF CLEVELAND, OHIO.

COFFIN.

SPECIFICATION forming part of Letters Patent No. 242,699, dated June 7, 1881.

Application filed March 4, 1880. (Model.)

To all whom it may concern:

Be it known that we, EDWARD H. SAXTON and THOMAS C. QUAYLE, of Cleveland, in the county of Cuyahoga and State of Ohio, have 5 invented certain new and useful Improvements in Coffins and Caskets; and we do hereby declare the following to be a full, clear, and exact description of the invention, such as will enable others skilled in the art to which it 10 pertains to make and use it, reference being had to the accompanying drawings, which form part of this specification.

Our invention relates to coffins and caskets; and it consists in attaching to the coffin or casket, either upon its sides or ends, a removable 15 shelf.

The object of the invention is to furnish a support for flowers, either in vases or made into ornaments.

20 In the drawings, Figure 1 is a view in elevation of a casket constructed according to our invention. Fig. 2 is an end view, showing the manner in which the end of the casket may be raised to admit of the storage of the shelf, 25 and also of its leg or support.

In the said drawings, A represents the body 30 of a coffin or casket, and B a shelf, which, in this instance, is permanently attached, either by hinges or in any other suitable method, to the end of the casket. This shelf is supported by the leg or legs C, bearing against the bottom of the shelf and against the end of the coffin.

Our invention may be varied in a number of 35 ways. The shelf may either be supported by a bracket, which may, in turn, be operated by

a spring and turned into position to support the shelf when the same is raised from the coffin, or it may be a shelf removably attached to the coffin by eyes and hooks, and after it 40 has served its purpose may be quickly removed from the coffin.

We do not limit ourselves in any degree to the construction of the shelf, or to what portion of the casket it may be attached.

45 We have found it convenient to recess the end of the casket, as shown in Fig. 1, and fitting a shelf thereto, which, when closed, forms the end of the coffin itself, and is unobserved. When in use it is raised and the leg or support C placed in position, when it is ready for the reception of such articles as taste and inclination may suggest.

50 The shelf or support B may be ornamented in any manner desired.

55 What we claim is—

As an article of manufacture, a coffin, casket, or burial-case having attached to it one or more shelves or brackets constructed to be folded or closed against said coffin when not 60 in use, and to be opened or projected to receive flowers or other ornaments or decorations, as shown.

In testimony whereof we have signed our 65 names to this specification in the presence of two subscribing witnesses.

EDWARD H. SAXTON.
THOMAS C. QUAYLE.
